UNITED STATES PATENT OFFICE.

LUTHER E. HOOVER, OF WOOSTER, OHIO.

ELECTRIC LANTERN FOR VEHICLES.

1,096,534.

Specification of Letters Patent. Patented May 12, 1914.

Application filed March 20, 1913. Serial No. 755,772.

To all whom it may concern:

Be it known that I, LUTHER E. HOOVER, a citizen of the United States, residing at Wooster, in the county of Wayne and State of Ohio, have invented a new and useful Electric Lantern for Vehicles, of which the following is a specification.

My invention relates to electric lanterns for vehicles, especially for use with top-buggies or carriages. Its object is to provide a simple and inexpensive electric lantern adapted to be detachably secured to the front bow of a buggy top and in such manner as to be readily adjustable so as to direct the rays of light therefrom in any desired direction, and secondly, to provide improved means for constructing such lantern so as to shield the electric bulb and increase the efficiency of the reflector.

It consists of the several novel devices hereinafter particularly described and illustrated and stated in the appended claims.

My invention is illustrated by the accompanying drawings, in which similar letters and figures of reference indicate like parts.

Referring to the drawings, Figure 1 is a sectional and side view of my lantern, in operative position. In this figure the lantern, the bow of the buggy top, and one of the hollow clamping forks are shown in section. Fig. 2 is a front view of my device with a part of the bow of the buggy top broken away. Fig. 3 is a perspective of the buggy top showing the lantern in position for use.

In the drawings, 1 is the body portion of the lantern which is constructed of any suitable sheet metal, slightly conical, and open at its larger end; 2 is a circular reflector mounted within the lantern body so as to be removable therefrom at pleasure; 8 is a conical shaped block fitted into the smaller end of the lantern body and there secured by suitable screws *u u*; 9 is a cross-section of a circular plate of non-conducting material; and 7 is an electric bulb and 10, electric wires, such as are commonly used for electric lighting.

The plate or block 9 is preferably made of porcelain; it is provided with a threaded socket into which the stem of the bulb 7 is threaded, as shown in Fig. 1, to establish electrical connections with the battery wires 10, in the usual and well known way; a neck 16 extends upwardly from said plate 9 thereby extending said socket and at its terminus, forming a base whereon the reflector 2 is

located, and the latter is perforated to register with said socket; the bulb 7 is provided with a flange 15 immediately above said threaded stem adapted to rest upon and solidly secure said reflector in position between said flange and neck within said lantern body when said bulb is screwed into its normal position in said socket as aforesaid.

I am aware that removable reflectors for similar uses have been heretofore used, and such I do not broadly claim. My improvement in this respect lies in securing the reflector in position independently of the lantern body and of the electrical connections so as to be more readily and inexpensively adjusted and secured than heretofore, and also to provide more easy access to the electric wire connections upon the plate 9 by simply unscrewing said bulb from said socket; and also to provide means for securing the support A by the plate B and bolts *b* to the lantern body and electrical mechanism aforesaid, all of which I accomplish by securing said reflector as stated independently of the lantern body and the said electrical connections.

For convenience the battery may be located in the usual box under the buggy seat, or it may be inclosed in any suitable receptacle and stored within the buggy box; the electric wires leading therefrom to the lantern may be attached along the bow 12 of the buggy top, and thence pass through an orifice of the lantern body to the electric poles which are located underneath the reflector 2 as shown in Fig. 2.

Electric connections or circuit being established by the insertion of the bulb 7 as aforesaid, the electric current may be turned on and off by means of a knob or key situated at any suitable point between the lantern and battery in the usual well known way. The batteries I employ for the purpose, are of the dry variety in common use, and may be either single or double according to the power required; and, as no claim is made by me to these well known features used in electric lighting, further description of the same is unnecessary.

For the purpose of adjustably and detachably securing my lantern to the top of a buggy, I construct the bifurcated support A having a flat base portion B to which the lantern body is securely attached by means of suitable bolts *b b* which pass through block 8 and plate 9, as shown in Fig. 1,

thereby fastening the parts solidly together. The support A extends at right angles outwardly from the lantern body 1 a distance sufficient to form a convenient handle for carrying the lantern when detached from the buggy. It is forked at its outer end, the forks 3 3 being made thin and flat and resilient near their junction. The under sides of their outer ends 5 5, respectively, are hollowed and fitted to receive and engage a metallic ball 4, which is provided with a threaded screw 6 whereby it may be secured to the upper portion of the bow 11, as shown in Fig. 1. A threaded thumb screw 8 passes through the forks 3 3, affording means for adjusting or detaching the support A upon the ball 4.

It is apparent that by means of the ball and double socket connection, the lantern body may be solidly secured to the buggy top, adjusted to any desired angle or direction, as indicated by the arrows c d, so as to direct the rays of light from the lantern reflector to suit the needs of the driver of the carriage, either while driving, or when making examination of team, road or carriage in time of darkness. The lantern body being extended forwardly beyond the electric bulb, not only protects the same but also tends to concentrate the rays of light in the given direction, and thus, by the several means described, a very useful and convenient lantern is provided, suited to the many needs of carriage driving in darkness.

I am aware that the use of a ball and socket joint and connection is not new, and such I do not specifically claim. But I am not aware that such has been used in connection with an arm support, such as shown at A, adapted to form a handle for carrying the lantern when detached—said handle terminating at one end in a flat base to which the lantern body is solidly secured as aforesaid, and at the other, in rounded forked terminals suitable for easy handling of said lantern when detached, and also for adjust-

ably securing the same in position as aforesaid.

Having thus fully described my invention, what I claim as new and desire to secure by Letters Patent is—

1. In an electric lantern, the combination with the lantern body, electric wires connected therewith, and a flat base projected outwardly therefrom as a handle, of a non-conductor plate within said body provided with a threaded neck socket and means for establishing electrical connections, a concave reflector removably mounted on said neck and apertured to register with said socket, an electric bulb adapted to be threaded into said neck-socket to thereby establish electric circuit between said wires, said bulb having a flange at its base adapted to rest upon and secure said reflector removably within said lantern body, and means for securing said plate and said body to said base, substantially as set forth.

2. An electric lantern, comprising, in combination with a lantern body, electric wires connected therewith, a non-conductor plate having a projecting neck with threaded socket therein and electrical connections, an electric bulb having a circular flange at its base and a stem adapted to be screwed into said neck socket to circuit said wires, a concave reflector within said lantern body mounted and removably secured between said neck and said flange, and aperture to register with said socket; a handle support for said lantern body secured thereto and to said non-conductor plate by connecting bolts, and means, including said handle, for adjustably securing said lantern in position at the top of a vehicle, substantially as set forth.

In witness whereof, I have hereunto set my hand this 26 day of February, 1913.

LUTHER E. HOOVER.

In presence of two witnesses:

HIRAM B. SWARTZ,
MAILON ROUCH.
